US00D919388S

(12) **United States Design Patent** (10) **Patent No.:** **US D919,388 S**
(45) **Date of Patent:** **** May 18, 2021**

(54) **RIVET REMOVAL TOOL**

(71) Applicant: **Jamey A Hall**, Simi Valley, CA (US)

(72) Inventor: **Jamey A Hall**, Simi Valley, CA (US)

(73) Assignee: **Jamey A. Hall**, Simi Valley, CA (US)

(**) Term: **15 Years**

(21) Appl. No.: **29/689,177**

(22) Filed: **Apr. 27, 2019**

(51) LOC (13) Cl. **08-05**

(52) U.S. Cl.

USPC **D8/14; D8/47**

(58) **Field of Classification Search**

USPC D8/14, 25, 51, 47, 98, 107, 300, 303

CPC Y10T 29/5118; B21J 15/383; B21J 15/00;

B21J 15/38

See application file for complete search history.

(57) **CLAIM**

The ornamental design for a rivet removal tool, as shown and described.

DESCRIPTION

FIG. 1 is a Perspective view of my new design;
FIG. 2 is a partial rear perspective view of FIG. 1;
FIG. 3 is a side elevational view of my design shown in FIG. 1;

FIG. 4 is a front view of FIG. 1;

FIG. 5 is a rear view of FIG. 1;

FIG. 6 is a magnified view of the section 6 identified in FIG. 3; and,

FIG. 7 is a perspective magnified view of the section 7 identified in FIG. 1.
